(57) **CLAIM**

The ornamental design for a bollard luminaire, as shown and described.

DESCRIPTION

FIG. 1 is a perspective view of a bollard luminaire, showing my new design;

FIG. 2 is a front elevation view thereof, with the rear elevation view being a mirror image of the front elevation view

FIG. 3 is a right-side elevation view thereof, with the left-side elevation view being a mirror image of the right-side elevation view;

FIG. 4 is a top plan view thereof; and,

FIG. 5 is a bottom plan view thereof.

The broken lines shown represent unclaimed subject matter and form no part of the claimed design.
